ELECTRICAL PLUG CAP OR SIMILAR ARTICLE

Daniel B. Miller, Providence, R.I.

Application September 23, 1958, Serial No. 52,733

Term of patent 7 years

(Cl. D26—1)

FIG. 1

FIG. 2

FIG. 3

FIG. 4

Figure 1 is a perspective view of an electrical plug cap or similar article, showing my new design;

Figure 2 is a side elevational view, the opposite side being substantially a mirror image thereof;

Figure 3 is a bottom plan view; and

Figure 4 is a top plan view thereof.

The dominant features of my new design are shown in solid lines in the drawings, the prongs shown in broken lines being omitted from Figure 3 for convenience in illustration.

The broken line fragmentary showing of a connecting cord is for illustrative purposes only.

I claim:

The ornamental design for an electrical plug cap or similar article, as shown and described.
